APPARATUS FOR MANUFACTURE OF
WELDED TERMINAL RESISTORSFredrick Isaac Ellin, Chicago, Ill., assignor to
David T. Siegel, Glencoe, Ill.

Application February 2, 1950, Serial No. 142,070

14 Claims. (Cl. 219—4)

1

This invention is concerned generally with resistors and like electrical units, and more particularly with an improved wire-wound resistor as an article of manufacture and with means and methods for manufacturing the same.

Small electrical resistors, such as are used in electrical circuits of comparatively low power, are of many types. Precision resistors wherein the resistance is controlled within rather close limits are frequently of the wire-wound type. These resistors are generally made by winding resistance wire on a ceramic core. The ends of the wire element are welded or otherwise electrically and mechanically connected to metallic bands encircling the core near the ends thereof. Each band comprises a strip of sheet metal bent around the core with the ends extending radially outwardly from the core and welded or otherwise secured together to form a terminal lug for mounting the resistor and making electrical connections thereto. As the bare resistance wire could be readily damaged or shorted out, the wire, core and bands are generally coated with a vitreous enamel and the resistor is then fired to glaze the enamel.

Certain difficulties are encountered in manufacturing resistors of the foregoing type. The firing of the resistors oxidizes the terminal lugs so that they must be cleaned and tinned before lead wires can be soldered to them when the resistor is installed. To prevent cracking of the core or loosening of the terminal bands, it is essential that the bands should have a coefficient of thermal expansion approximately the same as that of the core and coating. Metals which meet this requirement are often not suitable for soldering, are not sufficiently conductive and may possess other undesirable qualities. For different sizes of resistors, different lengths of bands and integral lugs must be provided, and there must also be provided a large number of different types of terminal bands to provide the different types and shapes of mounting lugs required.

It is an object of this invention to obviate all of the above enumerated faults and others, by providing a resistor with terminal bands having only short integral projections extending therefrom and a terminal lug or tab welded to each projection.

Another object of this invention is the provision of means and methods for producing the resistor set forth in the foregoing object.

A more specific object of this invention is the provision of a resistor having a terminal band

2

which has a short integral projection and a terminal lug or tab butt welded thereto.

Another specific object of this invention is the provision of means and methods for manufacturing the resistor set forth in the foregoing object.

The exact dimensions and the positioning of the terminal lug and band extension relative to one another are not of great importance as far as the finished product is concerned, and it would be needlessly expensive to control these dimensions and their positioning closely. However, it is desirable that an accurately controlled engagement be effected between the parts during the welding operation, to insure the formation of a proper welded connection.

An object of this invention is the provision of means for resiliently placing a terminal lug against the extension of a resistor terminal band while welding the lug and extension together.

As noted heretofore, the firing of the vitreous enamel on a wire wound resistor oxidizes the exposed lugs or extensions of the terminal bands. The oxide is a poor conductor of electricity. It would be possible to insure a good welding contact to the band extensions by mechanical clamps, and if this were done, it would be necessary to control the thickness of the band extensions within rather narrow limits. This would cause unnecessary manufacturing expense as the thickness of the extensions is of no practical significance within wide limits in the finished product.

An object of this invention is the provision of resilient clamping means for gripping and insuring good electric contact with the oxidized extension of a resistor terminal band.

A further object of this invention is the provision of means for welding terminal lugs to the integral extensions of the terminal bands of resistors, the means entirely automatic once a cycle of operation is started.

Other and further objects and advantages of the present invention will be apparent from the following description when taken in conjunction with the accompanying drawings in which:

Figure 1 is a perspective view of my welding mechanism and resistor at the start of an operational cycle;

Fig. 2 is a fragmentary top view partially in section taken along the line 2—2 of Fig. 1;

Fig. 3 is a cross-sectional view taken along the line 3—3 of Fig. 1;

Fig. 4 is a sectional view taken along the line 4—4 of Fig. 3;

Fig. 11 is a perspective view of the jaws for securing the terminal lug during welding;

Fig. 12 is a view of the jaws for securing the terminal band extension;

Fig. 13 is a perspective view of one of my resistors prior to the welding of the terminal lugs thereon, the vitreous enamel coating being omitted for clarity of illustration;

Fig. 14 is a view similar to Fig. 13 after the lugs or tabs have been welded on;

Fig. 15 is a fragmentary view of a resistor showing a different type of tab or terminal lug;

Fig. 16 is a view similar to Fig. 15 showing another type of tab or lug;

Fig. 17 is a cross sectional view as taken along the line 17—17 of Fig. 14, the vitreous enamel being shown;

Fig. 18 is a schematic wiring diagram of an electrical control circuit for operating my mechanism; and

Fig. 19 is a pneumatic circuit operated by the electrical circuit shown in Fig. 18 and operating my mechanism.

Stated briefly, the method and mechanism for welding terminal lugs or tabs to terminal band extensions or projections of resistors includes structure for supporting a resistor and resiliently gripping a terminal band extension, and structure for resiliently gripping a lug to be welded thereto. The band extension is forced against the lug by resilient pressure and a welding current is supplied between the band extension and tab. At the same time a hydrogen flame is played on the weld to prevent oxidation of the weld and tab surfaces in order to produce a finished product which is neat in appearance and which may be soldered readily. Upon completion of the weld, the welding current is turned off and is soon followed by extinction of the hydrogen flame. The lug and band extension are then released and the operating parts are returned to their initial positions.

For best understanding of this invention, attention should first be directed to Figs. 13-17 wherein resistors and various terminal lugs are shown. In Fig. 13 is shown a resistor 20 comprising a ceramic core 22 on which is wound a wire resistance element 24. The wire is welded or otherwise secured at each end to terminal bands 26 and 28. The bands comprise strips of sheet metal which are bent around the core and have upstanding extensions or projections 30 and 32 which comprise the ends of the bands bent upwardly and spot welded as shown at 34 in Fig. 17 or otherwise affixed together. The resistor is shown in Fig. 14 with terminal lugs or tabs 36 and 38 butt welded to the extensions 30 and 32, respectively. In Fig. 14 the terminal lugs are shown as being of substantially the same width as the bands 26 and 28. A fragment of a similar resistor 20 is shown in Fig. 15 wherein a tab 36a

is welded to an identical extension 30 on a band 26. In this case the lug is of greater width than the band for different installation requirements. A different type of tab 36b which is wider than the band 26 and extension 30 and is essentially L-shaped for still different installation requirements is shown in Fig. 16. In each of Figs. 13-16, and in the apparatus views subsequently to be described, the vitreous enamel coating has been omitted so that the winding of the resistance element and the placement of the terminal band may be seen readily. It is to be understood, however, that normally prior to the tab welding operations, the vitreous enamel would cover the wire winding and the terminal bands but not the extensions 30, 32, as shown at 37 in Fig. 17, and that these extensions would be in oxidized condition by the firing of the enamel.

For an understanding of the means and method of producing the resistor shown and described, reference should be had next to Figs. 1-12 and more particularly first to Fig. 1 wherein a resistor 20 having one tab 38 already welded in place is shown in position on the welding mechanism for the start of an operational cycle to weld the other tab 36 in place. The mechanism comprises a table 40 having situated near the rear end thereof a bifurcated block 42 secured by means such as screws 44 (Fig. 6). As will be apparent hereinafter, the table 40 is preferably made of some insulating material which may, for example, be wood. The table 40 may be mounted or supported in any desirable manner and support means are not shown except for clamping arms 46.

The means for holding the resistor comprises an arm 48 of conductive material which is preferably of low resistance, pivotally secured within the arms of the block 42 by a pintle 50. Welding current is supplied to the arm 48 by means of a cable 52 and terminal connection 54 which may be secured by means such as a screw 56 to the rear end of the arm. A pin 58 extends rearwardly from the arm 48 (Fig. 6) and a tension spring 60 is connected between this pin and a spring mounting bracket 62 secured to the underside of the table as by screws 64 normally to bias the arm upwardly. An adjustable stop 66 comprising a bracket 68 and set screw 70 may be secured to the block 42 to limit the upward movement of the arm 48. The free end of the arm 48 includes a head 72 to which is secured a mandrel 74 on which the resistor is placed. The mandrel is preferably removable so that a single machine may be adapted to accommodate a variety of resistors.

To effect the proper angular positioning of the resistor terminal band extension to be welded, a clamp 76 (Fig. 3) is secured by an arm 78 forwardly of the head 72. The clamp comprises a supporting member 80 fixedly secured to the arm 78 and a jaw 82 which is secured by a screw 84 fitting through an elongated slot in the jaw 82 and threaded into the support member 80 and is adjusted by a screw 86 which may be locked in place by a jam nut 88. For convenience of adjustment the screw head and nut may both be knurled. The band extension to be welded is arranged to be clamped against the jaw 82, by means subsequently to be described, and positioned thereby for the welding operation.

Means is provided for depressing arm 48, and simultaneously clamping the resistor band extension. More particularly, adjacent the head 72 the arm 48 carries a bifurcated bracket 90 in-

cluding an upper arm 92 and a lower arm 94, the former extending farther than the latter and carrying an adjustable screw 96 which may be locked in position by a jam nut 98. The screw 96 abuts against a stop 100 secured to the table 40 to limit the downward movement of the arm 48. Adjustable screws 102 and 104 are carried opposite one another by the upper and lower arms respectively for abutment by a finger 106 radially secured to and operable to limit the rocking motion of a shaft 108. The shaft 108 is journalled for pivotal movement in the arm 48, the portion of the shaft passing through the arm 48 being of reduced diameter as at 110 to preclude axial motion of the shaft in one direction. The other end of the shaft is reduced in diameter to an even greater extent and is provided adjacent its extremity with an operating arm 112 to which it is secured as by being pinned to a collar 114 integral with the arm 112 for rotation therewith. A cam member 116 is secured to the arm 112 (Figs. 2 and 5) adjacent the rear end thereof. A clamping arm 118 is pivotally secured by the bracket 90 and carries at its rear end a roller 120 abutting against the cam 116. A coil spring 122 carried within a recess 124 in the arm 48 abuts against the clamping arm 118 to force the roller 120 against the cam 116. A screw 126 threaded through the arm 118 prevents displacement of the abutting end of the spring 122. The opposite end of the arm 118 carries a clamp 128 comprising an adjustable jaw similar to the jaw 82 of the clamp 76. By means of the connections described, as arm 112 is actuated to lower the main support arm 48, cam 116 operates to project clamp 128 against the terminal band extension.

The means for operating arm 112 comprises a double acting air cylinder 130 containing a piston mounted on a bracket 132 secured to the table 40 by means such as bolts 134. The cylinder 130 is provided with air supply lines 136 and 138 and has the piston rod 140 extending downwardly from its lower end. The piston rod 140 has a connection 141 for determining its length and is provided at its lower end with a connection including a transverse stub shaft 142 slidably and rotatably secured within an elongated slot 144, Fig. 6, adjacent the end of the arm 112 opposite from the cam 116.

The remainder of the welding mechanism is located on the table 40 and includes a terminal lug or tab securing nest 146 including a cylinder 148 (Figs. 1, 3 and 6) projecting through the table and secured thereto as by a collar 150 which may be integral with the cylinder or affixed to it in any desired manner. The collar is in turn secured to the table by any desirable means such as by screws 152. The bottom of the cylinder is closed by an end piece 154 which carries an adjusting screw 156 which may be locked in position by means of a set screw 158. The adjusting screw 156 impinges upon a spring abutment member 160 comprising a flat disc having a central raised portion thereon. The abutment member 160 supports a compression spring 162 which encircles the central raised portion of the abutment member and pushes upwardly against a clamp or jaw supporting member 164. The member 164 has a flange 166 of enlarged diameter near its lower end cooperable with a shoulder 168 in the bore of the cylinder 148 to limit upward movement of the member 164. At its extreme lower end the member 164 is provided with an extending portion 170 of small

diameter to locate the spring 162. The lower portion of the member 164 may be provided with a central bore 172 in order to reduce the weight and inertia of the member. The member 164 is

5 bifurcated at its upper end and carries a clamp or jaw 174 fixed thereto as by pins or screws 176 passing through the member 164 and the jaw 174. A tongue 178 extends laterally from the jaw 174 and has a cable 180 secured thereto. 10 A second clamp or jaw 182 is pivotally secured to the member 164 in opposed relation to the jaw 174 as by a diametral pin 184.

The member 164 is radially apertured a short distance below the table 40 to threadedly receive 15 the reduced end portion 186 of a spring loaded cylinder 188. The spring is retained in the cylinder by an end piece 190 which may be threaded into the cylinder or secured by a pin 192 or secured in any other desired fashion. The spring 20 194 forces a piston 196 and a piston rod 198 normally to the right as seen in Fig. 3. The piston rod has its extremity abutting against the lower end of the clamp or jaw 182 to force the upper part of the jaw into clamping engagement with the jaw 174. The cylinder 148 is provided with an elongated longitudinal aperture 200 accommodating the spring loaded cylinder 188 for up and down movement.

A short distance to the right of the tab receiving nest 146 as seen in Fig. 3 is a double acting pneumatic cylinder 202 secured to the under side of the table 40 by a mounting bracket 204 and screws 206. A piston rod 208 extends from the cylinder 202 toward the nest 146 and 30 has secured to it a bifurcated bracket 210 in sliding engagement with the underside of the table 40. The bifurcated bracket 210 carries a roller 212 on a horizontal axle 214. The roller 212 at all times abuts against the flat end of a solid 35 cylindrical member 216, Fig. 4, having a reduced end portion 218 threaded into the clamp or jaw 182 opposite the piston rod 198. The cylindrical member 216 fits within an elongated longitudinal aperture 220 in the cylinder 148 for up and down movement. It should be noted that such movement is sufficiently restricted that a horizontal line through the center of the roller 212 always passes through the cylinder 216.

In Fig. 1 may be seen a nozzle 222 for discharging hydrogen directly above the nest 146 and upon the weld as it is being made. A spark ignitor 224 is carried by the table adjacent the nozzle 222 to ignite the hydrogen jet to prevent oxidation of the weld and terminal or tab surfaces to produce a clean neat appearing product which may be soldered readily.

Before proceeding to the control circuits and the operation of the apparatus, attention should be directed to Figs. 11 and 12 for further details 60 of the jaws 174 and 182 and the jaws 82 and 128. Aside from the details already disclosed, it will be seen that the jaw 174 is provided at its upper end with a rectangular recess 226 which facilitates the placement of a terminal lug or tab in position to be welded. An extending section 228 on the upper portion of the jaw 182 cooperates with the recess 226 to clamp a tab as will be apparent hereinafter. The clamp 82 may be seen in Fig. 12 to have an extending portion 65 230 of comparatively small vertical dimension in order best to clamp a band extension 30, 32 of the resistor. The extending portion 230 is provided with a clamping surface 232 and a tongue 234 extending therebeyond. The tongue 70 234 is narrower in its lateral dimension than the

clamping surface 232 so that a terminal band extension may be clamped centrally of the extending portion 230. The cooperating clamp 123 is provided with a thin extending portion 233 similar to the portion 230 of the clamp 82. The portion 236 is provided with a clamping surface 238 of the same lateral dimension as the clamping surface 232 and with a notch 240 to receive the tongue 234.

The pneumatic cylinders 130 and 202 along with their associated controls are shown in Fig. 19. A storage tank 242 is supplied with air under pressure from any suitable pump which is not shown. A supply line 244 leads from the tank 242 to a four-way valve 246 controlling the operation of the cylinder 130. A control arm 248 extends from the valve 246 and is pivotally connected to the plunger 250 of a solenoid 252. The plunger 250 is normally pulled away from the solenoid 252 by a tension spring 254 anchored to any suitable fixed point 256. When the valve arm 248 is urged to the left as shown in Fig. 19, the lower end of the cylinder 130 is supplied with air under pressure through the line 244, the valve 246 and a supply line 258 at the same time the upper portion of the cylinder 130 is connected through a line 260 and the valve 246 to an exhaust line or port 262. When the valve arm 248 is moved to the right by energization of the solenoid 252, the upper end of the cylinder 130 is supplied with air under pressure through the line 260, valve 246 and line 244 while the lower end of the cylinder is open to the atmosphere through the line 258, valve 246 and exhaust 262, so that the piston and piston rod 140 are forced downwardly.

The cylinder 202 is supplied with air under pressure from the tank 242 through a supply line 264, a four-way valve 266 and either of lines 268 and 270. A valve arm 272 extends from the valve 266 and is pivotally connected to the plunger 274 of a solenoid 276. The plunger is normally held down as seen in Fig. 19 by a tension spring 278 secured to any fixed point 280. In this position the valve ports are so oriented that the line 270 is connected to the line 264 while the line 268 is open to the atmosphere through the exhaust port 282 so that the piston rod 208 is urged to the left and the jaws 174 and 182 are held out of clamping engagement. When the valve arm 272 is raised due to energization of the solenoid 276, the connections are reversed so that the left end of the cylinder 202 is supplied with air under pressure while the right end is open to the atmosphere to move the piston and piston rod 208 to the right to release the jaws 174, 182, permitting the spring 194 to act to bring the jaws into clamping engagement.

An electrical control circuit is disclosed in Fig. 18 whereby the operation of the apparatus is rendered automatic from start to finish of a welding cycle. Power is supplied through a pair of supply lines L1 and L2; and the solenoids 252 and 276 previously referred to are connected in parallel to the line L2 and are in series with a switch driving motor 284 which is connected through push button switches 286 and 288 to the supply line L1. The switches 286 and 288 are located sufficiently far apart that both hands must be used to actuate them so that it is impossible for an operator to get his hands caught in the machinery. A switch arm 290 is connected to the line L1 through a line 292 and is driven in a clockwise direction by the motor 284 as is indicated by the dashed line 294. The mo-

tor driven switch circuit extends from line L1 and is completed to line L2 through a plurality of arcuate contacts, there also being an insulating or non-connected contact 296. A contact 298 is connected through lead wire 300 and lead wire 302 to an auxiliary switch actuating solenoid 304. The circuit from the solenoid 304 is completed by a line 306 to the line L2. Energization of the solenoid 304 pulls a switch member 308 into contact with switch points 310 and 312 to complete a circuit in parallel with the push buttons 286 and 288. A pilot light 314 is connected in parallel with the solenoid 304 and may be a distinctive color such as red or amber to indicate that the welding apparatus is operating automatically. Arcuate contact 316 is connected to a relay 318 controlling the welding current and the relay 318 is in turn connected to the line L2. Arcuate contact 320 is connected to a relay 322 controlling the hydrogen jet and the electrical circuit is completed through the relay 322 to the line L2. The remaining contact 324 is connected to a relay 326 controlling the spark gap to ignite the hydrogen jet and the relay 326 is in turn connected to the line L2.

To carry out a welding operation, the operator places a terminal lug or tab 36 loosely between the jaws 174 and 182 (Figs. 1 and 7). At this time the porting of the valve 266 is arranged due to the spring 278 so that air under pressure is supplied to the right end of the cylinder 202 to force the piston rod 208 to the left to pivot the jaw 182 into unclamping position. Due to the action of the spring 254 the ports of the valve 246 are so located that the piston rod 140 is forced upwardly. Upward movement of the arm 48 is limited by the stop 66 so that the lever or arm 112 is pulled upwardly by the piston rod 140 and pin 142 to force the rear end of the arm 112 and the cam 116 downwardly. The cam thus forces the roller 120 and the rear end of the clamping lever 118 against the action of the spring 122 (Figs. 2 and 5). This holds the jaw 128 away from the jaw 82 as seen in Fig. 7. A tab is fitted within the recess 226 and will abut against the bottom end thereof to prevent it from falling out. A resistor, complete except for the tabs is placed on the mandrel 14 with the projection 30 of the band 26 abutting against the clamping surfaces 232 and 234 of the jaw 82. In most cases the resistor has been coated with a vitreous enamel and fired, so that the tab surface is oxidized. To present a clean welding surface, the end of the projection is clipped off prior to placement of the resistor on the mandrel. The operator next pushes the pushbuttons 286 and 288 simultaneously. As noted previously, the switches are sufficiently far apart that both hands must be used as is indicated by R and L on Fig. 18. This completes the circuit through solenoids 252 and 276 to reverse the porting through the valves 246 and 266 respectively, to force the piston rod 140 down and the piston rod 208 to the right. The movement of the piston 208 to the right allows the spring 194 to force the jaw 182 into clamping relation with the body 176 to grip the tab 36 as may be seen in Fig. 8. The spring accommodates any variations in thickness between tabs. Downward movement of the piston rod 140 first pivots the arm 112 counterclockwise as seen in Fig. 6 to move the cam 116 (Figs. 2 and 5) upward to allow the spring 122 to move the body 128 into clamping relation with the body 82 to clamp the extension 30 of the resistor terminal band 26

(Figs. 3 and 8) to make contact through the oxidized surfaces thereof, with the spring 122 accommodating any variations in thickness between projections.

As the piston rod 140 continues its downward movement the pivoting of the arm 122 rotates the shaft 108 until the finger 106 strikes the stop 104. This stops the pivoting of the arm 112 and the arm 48 is moved downwardly about its pivot to lower the head 72 and force the terminal band extension 30 against the tab 36 (Figs. 3, 6, and 8). The jaws 174 and 182 are forced downwardly a short distance against the action of the spring 162. The spring allows the band projection and tab to be forced into firm engagement without crushing or bending either the extension or the tab. At the same time the solenoids 252 and 276 are energized, the motor 284 is started in operation to drive the switch arm 290. The switch arm moves over the insulating or non-connecting contact 296 during the clamping of the terminal band extension and the lug or tab and the downward movement of the head to bring the extension and tab into resilient contact. After leaving the contact 296 the arm simultaneously contacts the arcuate contacts 298, 316, 320 and 324. This energizes the auxiliary switch solenoid 304 to complete the motor circuit independently of the push button switches 286, 288 and at the same time lights the pilot light 314 to inform the operator that he can release the push button switches after this time as there is no further clamping or moving together of parts to endanger the operator's safety. Simultaneously as the several arcuate contacts are engaged, the welding current starts, the hydrogen jet is turned on and the spark igniter becomes operative to ignite the hydrogen jet. After a short time the arm 290 leaves the contact 324 so that the spark igniter becomes inoperative but remains on the other contacts so that the motor, welding current and hydrogen jet remain in operation. After a predetermined interval, the switch arm leaves the contact 316 and the welding current is turned off. The motor circuit and hydrogen jet relay circuit are still completed for a short interval after which the hydrogen jet is extinguished as the switch arm leaves the contact 320. The arm still contacts the contact 298 at this time to continue the motor in operation. As the arm 290 leaves the contact 298 the auxiliary switch relay 304 is deenergized to stop the motor and the pilot light 314 is extinguished. The spring 278 retracts the plunger 274 to actuate the valve 266 to admit air under pressure to the right end of the cylinder 202 to force the roller 212 against the cylindrical member 216 to pivotally move the jaw 182 out of clamping relation with the jaw 174. At the same time the spring 254 retracts the plunger 250 to operate the valve 246 to admit air to the lower end of the cylinder 130 and force the piston rod 140 upwards.

The upward movement of the piston rod 140 along with the restoring force of the spring 50 forces the arm 48 upwards until it strikes its stop 66. When the arm 48 is stopped, the piston rod 140 continues to exert an upward force on the arm 112 which causes the cam 116 (Figs. 2 and 5) to react against the roller 120 and pivot the lever 118 to move the jaw 128 away from the jaw 182. Upward movement of the piston rod 140 is stopped when the finger 106 strikes the stop 102. When it is considered that the piston

rod 140 moves rectilinearly and any point on the arm 112 moves in a compound angular motion due to the pivoting of the arm 112 on the shaft 108 and the pivoting of the arm 48 on its pintle 50, the necessity of the slot 144 and pin 142 rather than a simple pivotal connection is obvious. When the head 72 reaches its upper limit the resistor 20 may be removed from the mandrel 74 and reversed to weld on another tab, or another resistor may be placed on the mandrel.

It should now be apparent that with the resistor and manufacture thereof herein shown and described, a plurality of resistors may be supplied with standard terminal bands of metal having a suitable coefficient of expansion to cooperate with the resistor core 22 and any of a wide number of different tabs suitably pre-timed and differing in size, shape or material may be supplied. With the means and method disclosed, the operation is entirely automatic once the tabless resistor and tabs have been placed in the apparatus and the operator has pushed the actuating buttons. The resilient mounting of the tab nest insures proper follow-up welding pressure between the parts, and the parts are always properly aligned so that a proper butt weld may be formed.

The claims in this case are directed to the welding apparatus. Claims to the resistor are presented in a divisional application.

Although certain specific embodiments of my invention have been shown and described herein, it is to be understood that these are for illustrative purposes only and that my invention is to be limited only within the spirit and scope of the following claims.

I claim:

1. Mechanism for manufacturing resistors comprising a base, an arm pivotally mounted on said base, rotatable means carried by said arm, means on said arm for supporting the projection of a metallic encompassing band on a resistor, means on said base for supporting a terminal to be welded onto said projection, means for rotating the rotatable means on said arm, means responsive to rotation of said rotatable means to operate the projection supporting means to support a projection, means effective after a predetermined degree of rotation of said rotatable means to pivot said arm to bring said projection and said terminal into contact, and means for welding said terminal to said projection.

2. Mechanism as set forth in claim 1 wherein the means effective upon predetermined rotation of said rotatable means to pivot said arm comprises a radial projection on said rotatable means and a fixed member on said arm engageable by said projection.

3. Mechanism as set forth in claim 2 wherein the means for supporting said projection comprises a clamp and the means for rendering the clamp effective to support a projection includes a cam.

4. Mechanism as set forth in claim 1 wherein the projection supporting means comprises confronting jaws having thin gripping edges for engaging a projection without encountering a resistor, and the terminal supporting means includes a pair of jaws resiliently urged toward the projection engaging jaws, resilient means normally urging the terminal jaws into engagement, and power means for opening said terminal jaws, both pairs of jaws having means for accurately positioning the projection and the terminal respectively.

11

5. Mechanism for welding a terminal onto a metallic projection of a resistor, comprising a pair of opposed jaws for gripping a resistor projection, said jaws having corresponding extending portions for accurately positioning a projection, means for closing said jaws on a resistor projection, a pair of opposed jaws for gripping a terminal to be welded on to said projection, one of said terminal gripping jaws having a recess for receiving and accurately positioning a terminal, and the other terminal jaw having a projection adapted to extend into said recess to grip a terminal, means for closing the terminal jaws on a terminal, means for relatively shifting the pairs of jaws toward one another to bring said terminal into engagement with said projection, and means for welding said terminal on to said projection.

6. Mechanism for applying a terminal to a projection on a resistor, and comprising means 20 for clamping the terminal, a support assembly for the resistor, means for mounting said terminal clamping means and said resistor support assembly for relative movement to bring the terminal and resistor projection into contact, drive mechanism for effecting the relative movement between the resistor support assembly and terminal clamping means, clamp means associated with said resistor support assembly for separately clamping the resistor projection, means 25 operable in response to operation of the drive mechanism for actuating said clamp means for independent movement relative to said resistor support assembly to clamp the resistor projection and operable to maintain the resistor projection 30 in clamped position during contact therewith the terminal, and means for welding the resistor projection to the terminal during contact.

7. Mechanism as claimed in claim 6, wherein the resistor support assembly includes a stud-like 40 member internally engaging and supporting the resistor.

8. Mechanism as claimed in claim 6, wherein means are provided for maintaining the terminal and resistor projection resiliently in contact with 45 one another during welding.

9. Mechanism as claimed in claim 6, wherein actuation of the clamp means for clamping the resistor projection is effected prior to relative movement between the resistor support assembly 50 and the terminal clamping means.

10. Mechanism as claimed in claim 6, wherein

12

the resistor support assembly and associated clamp means are movable toward and away from the terminal clamping means.

11. Mechanism as claimed in claim 10, wherein 5 the terminal clamping means is resiliently mounted to provide resilient contacting pressure between the terminal and resistor projection.

12. Mechanism as claimed in claim 6, wherein 10 there is provided a releasable connection between the drive mechanism and the clamp means effective to permit relative independent movement of the clamp means with respect to the support means for clamping and unclamping the resistor projection.

13. Mechanism as claimed in claim 6, wherein 15 the drive mechanism includes a lost motion connection with the support assembly and a releasable inter-engaging connection with said clamp means effective upon release to permit clamping movement of the clamp means during the lost motion cycle of the drive mechanism.

14. Mechanism as claimed in claim 6, wherein 20 the clamp means for the resistor projection is resiliently maintained in one position, and wherein the drive mechanism includes a releasable connection with the clamp means effective to permit movement of the clamp means to its other position.
